UNITED STATES PATENT OFFICE.

EDWARD F. NEEDHAM AND GEORGE W. SMITH, OF FORT WAYNE,
INDIANA.

STEAM-ENGINE VALVE.

No. 797,309.

Specification of Letters Patent.

Patented Aug. 15, 1905.

Application filed July 13, 1904. Serial No. 216,404.

To all whom it may concern:

Be it known that we, EDWARD F. NEEDHAM and GEORGE W. SMITH, citizens of the United States, residing at Fort Wayne, in the county of Allen, in the State of Indiana, have invented certain new and useful Improvements in Steam-Engine Valves; and we do hereby declare that the following is a full, clear, and exact description of the invention, which will enable others skilled in the art to which it appertains to make and use the same, reference being had to the accompanying drawings, which form part of this specification.

Our invention relates to improvements in steam-engine valves.

The primary object of our present invention is to provide a cheap, simple, efficient, and reliable engine-valve in which the communication between the working cylinder and the steam-chamber is controlled by two independently and oppositely movable cut-off valves so arranged as to effect this control in half the time required in a single piston-valve, thereby materially reducing the usual throttling of the initial steam, and secure the benefits of a large-throw eccentric without excessive wearing of parts.

Our invention consists of two independently and simultaneously movable cut-off valves in concentric relation and oppositely actuated, the outer valve being tubular and having duplicate ports at its opposite ends in constant communication with the cylinder-ports, the inner valve being independently movable in the tubular valve and adapted to alternately open and close the steam-ports of the tubular valve, and improved means for actuating the said cut-off valves simultaneously in opposite directions.

The principal novel feature of our invention resides in the construction arrangement and coöperative relation of the cut-off valves to each other and to the cylinder-ports.

Similar reference-numerals indicate like parts throughout the several views of the drawings, in which—

Figure 1 is a central section through an engine-cylinder and the valve-casing, showing the relative arrangement of the cut-off valves, steam and exhaust ports. Fig. 2 is an enlarged end view of the tubular cut-off valve, showing the spider in which the valve-stem is secured. Fig. 3 is an enlarged detail plan of the same, showing the arrangement of the

steam and exhaust ports. Fig. 4 is an enlarged view of the inner cut-off valve. Fig. 5 is a plan of the same, partly in section.

The cylinder-casting 1 has the usual or other proper arrangement of initial steam-ducts 2 and exhaust-steam ducts 3 and 4, Fig. 1, and a cylinder 5, having a working piston 6 and a piston-rod 7 of the usual construction.

In the casting 1 are rigidly fixed the duplicate tubular valve-casings 8 and 9, closed at their outer ends by the steam-tight heads 10 and provided near their outer ends with a series of peripheral exhaust-ports 11 in direct communication with the exhaust-steam ducts 3 and 4, respectively, and also provided near their inner end with a series of ports 12 and 13, respectively, which are in direct communication with the respective cylinder-ports 14 and 15. In these valve-casings 8 and 9 is slidably mounted the tubular valve 16, provided at each end with a series of duplicate peripheral ports 19 and 20, adapted to be at all times in register with the ports 12 and 13, respectively, of the valve-casing, and therefore at all times in full communication with the respective cylinder-ports 14 and 15. The valve 16 is also provided at its central portion with a series of extended peripheral steam-inlet ports 18 in direct communication with the steam-duct 2. This valve 16 is also provided with proper steam-tight packing-rings 24 and 25, Fig. 3, and has at its forward end a valve-stem 27, preferably tubular at its inner end to loosely contain the forwardly-extended end of the valve-stem 22 of the inner cut-off valve about to be described. The outer end of the valve-stem 27 is pivotally connected to one end of the walking-beam 28, which in turn is pivoted midway of its ends on the bracket 29. The other end of this walking-beam is pivotally connected with one end of the operating-rod 30, whose other bent end is pivotally connected to one end of a rocker-arm 31 by means of the pivot 34. The other end of the arm is pivotally connected with the rocker-shaft 32.

The inner cut-off piston-valve 21, cylindrical in form, has upon each end enlarged heads 23, provided with metal packing-rings 26. This valve is slidably and concentrically mounted in the tubular valve 16 and is adapted to alternately open and close the ports 19 and 20 of the tubular valve. The valve 21 has its rear end provided with a valve-stem 22, whose

outer end is pivotally connected to one end of the short rod 33, whose other end is pivotally connected to the arm 31 by means of the pin 34. The forward end of the valve 21 may be provided with an extension-stem 35, whose outer end plays loosely in the tubular end of the valve-stem 27 for the purpose of affording a bearing for the valve-stem 27, though the extension 35 is not essential and may be omitted.

The operation of our invention thus described is obvious and, briefly stated, is as follows: When power is applied to the rocker-shaft 32, it will simultaneously actuate the valves 16 and 21, the former through the medium of the arm 31, the operating-rod 30, the walking-beam 28, and the valve-stem 27 and the latter through the medium of the arm 31, the rod 33, and the valve-stem 22. Obviously these valves will be oppositely actuated simultaneously, whereby the opening and closing of the ports 19 and 20 of the tubular valve 16 will be effected in one-half the time required for a single valve, as the travel of each of these cut-off valves 16 and 21 in approaching and receding from each other in action requires of each but one-half the travel which would be required by a single valve. In Fig. 1 the tubular valve 16 is shown at the forward limit of its movement and the inner cut-off valve is shown at the rearward limit of its movement, in which position the cylinder is just beginning to take in initial steam at its rear end and to exhaust at its front end. The next movement of the tubular valve 16 is rearwardly, but only so far as to permit the ports 19 and 20 to remain in full register with the respective extended ports 12 and 13. The next and simultaneous movement of the valve 21 is forwardly, thereby closing the ports 19 to the exhaust and opening them to live steam, at the same time

gradually closing the ports 20 to the live steam and opening them for exhaust. This simultaneous movement of the coacting cut-off valves thus reduces their respective travel, secures a quick, reliable, and efficient action, reduces materially the usual throttling of steam, and specially adapts our invention for high-speed engines.

Having thus described our invention and its mode of operation, what we desire to secure by Letters Patent is—

1. In a steam-engine, means for controlling the admission of steam to the piston-cylinder, consisting of a pair of telescoping valves having a simultaneous and opposite reciprocation, and adapted to cut off the supply of steam at each stroke thereof; and means for actuating the said valves.

2. An engine-valve for controlling the supply of steam to the piston-cylinder consisting of a pair of telescoping cut-off valves in coöperative relation, the outer one having proper inlet and exhaust ports, the said valves being adapted for an opposite and simultaneous reciprocation, and means for actuating the said valves.

3. Means for controlling the admission of steam to the piston-cylinder of a steam-engine consisting of an inner and an outer valve arranged in a cylindrical valve-casing having inlet and exhaust ports, the said valves being in concentric and coöperative relation, and adapted for a simultaneous reciprocation in opposite directions for the purpose described; and means for actuating the said valves.

Signed by us at Fort Wayne, Allen county, State of Indiana, this 9th day of July, 1904.

EDWARD F. NEEDHAM.
GEORGE W. SMITH.
